PIVOTED SIDE-JAW WRENCH HAVING
MANUALLY-CONTROLLED SLIDABLE-
WEDGE LOCK

Ernest E. Cooper, La Fayette, R. I.

Application July 11, 1947, Serial No. 760,395

1 Claim. (Cl. 81—116)

1

This invention relates to a wrench of the type which is maintained in engagement with a nut or bolt head which it is desired shall be worked upon so that it will be unnecessary to remove the wrench for a fresh grip on the work.

Wrenches of this general type have usually been formed with some sort of ratchet which is relatively expensive to manufacture or the wrenches depend upon some spring action which may yield when heavy pressure is applied so as to become ineffective.

One of the objects of this invention is to provide a wrench which has the desirable quality of a ratchet wrench without a ratchet being used.

Another object of this invention is to provide a wrench which may be moved about the nut by releasing one of the jaws and which wrench will cause the movable jaw to follow back into engagement with the nut as relative movement of the wrench and nut occur.

Another object of this invention is to provide a thumb controlled member which may be moved to prevent relative movement of the jaws when in engagement with the work so that the required amount of torque may be applied to the work when desired.

Another object of this invention is to mechanically cause the thumb controlled member to move out of engagement with the movable jaw, it being only necessary to apply pressure of the thumb for locking the same in position.

Another object of this invention is to provide a construction which will be relatively simple to manufacture.

With these and other objects in view, the invention consists of certain novel features of construction as will be more fully described and particularly pointed out in the appended claim.

In the accompanying drawings:

Fig. 1 is a sectional view of the wrench;

Fig. 2 is a section on line 2—2 of Fig. 1;

Fig. 3 is a section on line 3—3 of Fig. 1;

Fig. 4 is a sectional view of the body member with the fixed jaws thereof;

Fig. 5 is a side elevation of the wrench;

Fig. 6 is a plan view of one of the movable jaws;

Fig. 7 is an end view of the jaws shown in Fig. 6;

Fig. 8 is a sectional view through one of the control members.

In proceeding with this invention, I provide a body member which is suitably slotted for the reception of the various movable parts which are mounted thereon. These movable parts con-

2

sist of a movable jaw to cooperate with the fixed jaw, carried by the body at either one or both ends, and a slidably mounted control member which moves into and from engagement with each movable jaw to hold it in gripping relation or move it to gripping relation. Springs may be provided causing the jaw to move in one direction and also a spring may be provided for causing the control member of the jaw to move in one direction, the thumb being used for moving the control member and in turn the movable jaw in the other direction. The structure may be formed of a solid piece of stock suitably grooved for the reception of the operating parts.

15 With reference to the drawings, 10 designates the body which is provided with fixed jaws 11 at either end which may be formed as one piece with the body. The movable jaw is designated generally 12 and consists of a portion 13 to cooperate with the fixed jaw 11, thus providing a surface 14 to engage the diametrically opposite portion of the work from the surface 15 of the jaw 11. This jaw 12 has a leaf portion 16 which will enter a slot 17 in the body portion 10 so that this leaf portion 16 will be pivoted by means of pin 18 for rocking movement relative to the body member 10. This leaf 16 is provided with an abutment arm 19 against which a spring 20 acts while the other end of the spring 20 acts upon an abutment 21 so as to swing the jaw 12 about the pivot pin 18 to move the surface 14 toward the surface 15. An arm 22 also extends from the jaw 12 and is of such shape that it will present a wedge-shaped opening 23 between the surface 24 and the edge 25 of the body 10.

A control member 26 has a wedge-shaped end 27 to slide into this wedge-shaped opening 23 to prevent movement of the movable jaw 12 clockwise, as shown at the left in Fig. 1, about its pivot. 40 This control member 26 has a portion which is substantially the same thickness as the body 10, while it has a tongue portion 28 which enters a groove in the body 10 to be guided in its movement along the edge of the body 10. This tongue is also provided with a slot 29 through which a pin 30 extends and which pin is fixed in the body. A spring 32 acts between this pin and one end of the slot so as to move the control member 26 away 45 from the movable jaw so that the jaw surface 14 can be moved out of nut gripping position. In order to limit the movement of the movable jaw 12 about its pivot, an abutment surface 35 (Fig. 4) is provided as a part of the recess for the reception 50 of the leaf 16 and the leaf is provided with an ear

36 (Fig. 6) to engage this abutment surface and limit the movement of the jaw about its pivot.

A duplicate construction but of a different size range will be provided at the opposite end of the body 10.

In operation, a nut will be engaged by the surfaces 14 and 15, the wedge or control member 26 will be moved so that the surfaces 14 and 15 cannot move apart, and then a torque may be applied on the nut. When it is desired to get a new grip, it is merely necessary to release the thumb from engagement with the control member 26, the spring 22 then causing it to move to the right as shown in the upper portion of Fig. 1 and then the body may be swung counterclockwise so as to move the surfaces 14 and 15 about the nut to obtain a new grip. This action will be permitted by reason of the spring 20 permitting the jaw to move about its pivot. When the wrench is adjusted for the new grip, the spring 20 will move the surfaces 14 and 15 into engagement with the surface of the nut to be gripped and then the wedge may be moved by the thumb so as to prevent separation of the surfaces 14 and 15 and the nut may then again be turned. This action may take place very rapidly by simple movement of the control member by the thumb as desired.

The jaw and control members may be very easily made of solid stock with the leaf or tongue cut down from opposite sides of the stock for the purposes desired. The body would be made of solid stock suitably slotted.

I claim:

In a wrench a longitudinal body member having fixed therewith one jaw of a nut receiving recess, a second jaw pivoted to said body member

on substantially the longitudinal center line thereof and rockable toward and from the fixed jaw, a stop to limit movement of the second jaw toward the first jaw, a spring to urge said second jaw against said stop, a control member slidably mounted on a longitudinal edge of said body and provided with a surface inclined to said longitudinal body edge, said surface, when said control member is manually moved relative to the body member, engaging the second jaw and urging it toward the first jaw to grip a nut, and a spring to retract said control member when manual pressure thereon is released, whereby said second jaw will swing against the action of its urging spring when the wrench is swung backwards around the nut in order to obtain a new grip thereon.
